CLAIM

The ornamental design for a phone case with positionable accessory, as shown and described.

DESCRIPTION

FIG. 1 is a front perspective view of the phone case with positionable accessory according to the present invention; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a bottom side view thereof;

FIG. 8 is a top side view thereof;

FIG. 9 is a front perspective view of a second arrangement thereof; and,

FIG. 10 is a front perspective view of a third arrangement thereof.

The broken lines are included for the purpose of illustrating environment and form no part of the claimed design.

1 Claim, 9 Drawing Sheets
